METHOD OF MAKING CROWN OPENERS.

APPLICATION FILED JULY 22, 1915.

Patented July 26, 1921.

UNITED STATES PATENT OFFICE.

EDWIN WALKER, OF ERIE, PENNSYLVANIA; JESSIE STERRETT AND MARY E. STEINER
ADMINISTRATRICES OF SAID EDWIN WALKER, DECEASED.

METHOD OF MAKING CROWN-OPENERS.

1,385,976.

Specification of Letters Patent. Patented July 26, 1921.

Original application filed July 19, 1910, Serial No. 572,681. Divided and this application filed July 22, 1915. Serial No. 41,375.

To all whom it may concern:

Be it known that I, EDWIN WALKER, a citizen of the United States, residing at Erie, county of Erie, and State of Pennsylvania, have invented a certain new and useful Method of Making Crown-Openers, of which the following is a specification.

This invention relates to a method of making crown openers, and the subject matter of this application is a division of a prior application filed by me on July 19, 1910, Serial No. 572,681, wherein the novel crown opener and method of making the same were described and claimed.

15 The invention embodies a method of making crown openers which consists in bending a metal rod or wire into a loop and swaging the metal at a plurality of points within the loop, thereby producing flat lips or offsets 20 which extend from the inner edge of said loop and are positioned substantially centrally of the wire rod, said swaging operation displacing the metal and producing recesses in the wire or rod. The invention 25 further embodies the method of making a combined cork screw and crown opener in the form of a unitary implement, in a simple, economical and efficient manner.

In the preferred manner of practising the 30 present invention, a portion of wire rod is bent to form a loop, while the remaining portion of the rod is formed to serve as a handle, and lips are swaged from that portion of the loop adjacent the handle, the 35 swaging operation being so conducted that the resulting lips will have substantially parallel faces, convex edges, and recesses will be formed in the wire or rod at the points where the metal is displaced to form the 40 lips. The recesses are thus in juxtaposition with the lips.

By forming the crown opener with two or more lips instead of one, as usual, the pressure employed in removing the crown is distributed to better advantage, whereby the 45 bottle is more easily opened and with less danger of breaking the neck or mouth of said bottle. Moreover, the crown or cap is not so liable to be distorted, thereby enabling 50 it to be replaced on the bottle, should this be desired. Furthermore, the flattened lips provide an extended and efficient bearing against which to apply pressure to the crown, while the adjacent recesses allow of 55 maximum engagement of the lips with the

crown, thereby aiding in the ready removal of the latter. By making the lips with parallel faces, either face of said lips may be employed in lifting the crown, thereby allowing of the removal of the crown in either 60 of the positions in which the crown opener may be placed upon the bottle.

The method of the present invention secures economy in the manufacture of crown openers, and the product is an extremely 65 simple device, strong, rigid, durable, and esthetic in appearance. The operations of forming the loop and swaging the lips are performed easily and rapidly by appropriate machinery, the time consumed in the manufacture of one of the devices being comparatively infinitesimal, and this is also true of the method when employed in the manufacture of combined cork screw and crown openers. In the latter case, the cutting of 70 the blank for the composite implement also effects a considerable saving of time and material.

In the accompanying drawings I have 75 illustrated the preferred manner of practising the present method, but the construction therein shown is to be understood as illustrative, only, and not as defining the limits of the invention.

Figure 1 shows a reel of wire from which 80 the openers are to be made, said reel being supported for rotation upon a suitable standard.

Fig. 2 shows a blank or length of wire rod, of the length necessary to form the opener. 85

Fig. 3 shows the rod after being formed into the shape desired for the opener.

Fig. 4 shows the completed article.

Fig. 5 is a section taken on line 5—5 of Fig. 4.

Fig. 6 shows the manner in which a length of wire is cut, if it's desired to construct a composite crown opener and cork screw.

Fig. 7 shows the wire after the cutting operation, and

Fig. 8 shows the finished implement.

Fig. 9 illustrates a modified form of composite crown opener and cork screw.

In making a crown opener A, as shown in Fig. 4, I preferably start with a reel of wire C, which is mounted on a suitable standard B, although straight wire rod may be employed. In either case, a piece of material c is cut from the source of supply, which piece forms the blank from which the crown 105

opener is to be made and is necessarily of such length as to form the completed opener. Blank *c* is then manipulated by suitable mechanism into the form or configuration which it is desired to make the finished crown opener, such, *e. g.*, as the shape shown in Fig. 3. The shape of the crown opener may greatly vary, according to taste, the essential feature being that a loop, such as *a*, be provided which may be passed over a crown positioned on the neck of a bottle, and with said loop must be associated some means for operating the same, such as a second loop or projection *a'*, shown in Figs. 3 and 4.

In bending blank *c* into the shape shown in Fig. 3, the free ends of said blank will be manipulated into end-abutting relation, and these ends are preferably not secured together in any way which will preclude their spreading apart, for reasons hereinafter specified.

Having completed these operations, the partially completed crown opener is positioned, by any suitable mechanism, or manually, in co-operative relation with a suitable press which, when actuated, swages out from the interior of loop *a*, a plurality of lips *d*, *d'* and *d''*, and in so doing, displaces a portion of the wire rod to form recesses *d³* adjacent each lip, as shown more particularly in Figs. 4 and 5.

Any desired press mechanism may be employed in forming the lips, but said mechanism is preferably such as will operate from both sides of the crown opener in such manner that the finished lips will have parallel faces with recesses adjacent each face. Such a formation is shown in Fig. 5 and is the preferable one, for the reason that the crown opener thus formed is reversible, *i. e.*, either face of the lips may be utilized in lifting the crown.

The form of the invention shown in Fig. 4 is that which it is preferred to make. The three lips *d*, *d'* and *d''* are so positioned that the lips *d* and *d'* are adapted for conjoint operation in removing the cap by a lifting movement, whereas the lip *d''* may be utilized alone in the removal of the cap by a depressing movement of the handle of the opener. However, while it is preferred to form the three lips in the manner described, the opener may be made either with two lips, such as *d* and *d'*, or with a single lip *d''*. Said lips being formed in the manner specified with substantially parallel faces and juxtaposed recesses will, in either embodiment of the invention, operate with an increased degree of efficiency, and will produce better results than have heretofore been possible.

In utilizing the lips *d* and *d'* in the removal of a crown, the loop portion *a* of the opener is applied to the neck of a bottle in

the usual manner so that the said lips engage with the bent in edge of the crown, and the handle portion *a* is then raised to remove the crown. When the lip *d''* is employed to remove the crown, the loop portion *a* of the opener is applied to the neck of the bottle, so that said single lip engages with the bent in edge of the crown, and the handle *a'* is thereafter depressed thereby removing the crown.

The forming of the crown opener in the manner specified produces a device embodying marked features of advantage over those heretofore employed. The swaging of the lips, due to the fact that the metal is very greatly compressed, makes them harder and thus greatly increases their durability. The positioning of the lips centrally of the metal composing the loop *a* adapts the implement to be used on either side to equal advantage; in other words, it is reversible. The forming of the lips with substantially parallel faces causes said lips to reach in under the corrugations of the bent-in edge of the crown, while the recesses adjacent said lips enable said corrugations to fit well over the lips and into the recesses, during the operation of lifting the crown. Moreover, the recesses also serve to limit the extent to which the lips project beneath the crown and preclude their contact with the neck of the bottle, thereby preventing the checking or cracking of the neck of the bottle.

A further feature of advantage is the fact that the free ends of the wire rod at the handle portion of the opener are disconnected, thereby enabling the opener to readily adjust itself to the contour of the mouth of the bottle when the opener is applied thereto, as in the act of removing the crown. The lips *d* are preferably convex or substantially semi-circular on their inner free edges, and such peculiarly formed lips, in conjunction with their proper spacement apart, secure the desired result of lifting the crown easily, without any tendency to chip the neck of the bottle.

From the foregoing description of the invention, it will be apparent that the different operations of forming the opener may be automatically performed by simple, well known mechanisms, and that, in the manipulation of the metal incident to the forming of the lips, the opener is strengthened rather than weakened, whereby the resulting article is strong and durable. The article can, manifestly, be economically and expeditiously produced, is esthetic in appearance, and embodies all the characteristics which go to make an ideal crown opener.

In carrying out the process described in its entirety, a device of maximum efficiency and utility is produced; yet, I am aware that the invention embodies many features, some of which might be employed without neces-

sarily using all. Accordingly, I do not limit the invention to the specific details shown and described, but consider the invention as broadly novel as commensurate with the appended claims.

I have hereinbefore described my process as embodying a plurality of steps, and have set forth the preferred sequence of these steps in the making of the opener. However, I do not wish to be understood as limiting myself to this particular sequence of operations, as they may be performed in different order.

In Figs. 6, 7 and 8 I have shown a slightly modified form of the invention, the steps of which process, when carried out, produce a combined crown opener and cork screw. In manufacturing the combined article shown in said figures, a metal rod or wire E of the desired gage and strength is employed. This rod or wire is drawn from a coil, and a length suitable for the purpose is cut off, the line of the cut being indicated at e^2 . Before, after, or during the operation of cutting off the length of wire or rod, the metal is cut or split lengthwise along the line e^3 , the line of division e^3 extending at its extremities in oppositely inclined directions, as at e^4 e^5 , whereby the cut length of material is separated into two distinct blanks e , e' , see Fig. 7. The method of making the blanks is not only rapid and economical, two blanks being produced at one operation from a single length of material, but by splitting the material in the manner described, the desired bevel and point e^4 e^5 of the cork screw is simultaneously produced in each of the two blanks.

The blanks having been produced, the split portion of each blank which forms the screw is wound or coiled around a suitable mandrel, but the cylindrical part of the blank is adapted to form the handle of the cork screw by bending the cylindrical part of the blank into a loop f.

Before or after bending the cylindrical part of the blank to produce the loop f, but preferably after the formation of the loop, the material of the loop is swaged at one or 50 more points by the operation of a suitable press, thus producing the recesses d^3 , and displacing the metal to form the flat lips or offsets d , d' and d^2 .

It will be obvious that the only distinction between the devices of Figs. 1 to 5 inclusive, and Figs. 6 to 8, inclusive, is that in the former case the crown opener is provided with a portion which serves as a handle only, whereas in the latter case the crown opener is provided with a handle in the form of a cork screw. In each instance, however, the crown opener embodies the essential features of a loop with one or more lips or off-

sets positioned and constructed in the manner specified for the purpose of supplying 65 pressure to the under edge of a bottle cap, when it is desired to remove the latter.

While it is preferable in forming the combined cork screw and crown opener from a blank which has been split, as described, the 70 article may be made from a blank which consists merely of a wire rod of the required length, which is pointed at one end. One portion of the rod in such case is bent to form the loop, the remainder of the rod 75 being bent to form the convolutions of the cork screw, and the loop swaged in the manner specified to produce the crown engaging lips as shown in Fig. 9.

Having thus fully described the invention, 80 what I claim as new, and desire to secure by Letters Patent, is:

1. The method of making an article of the class described, which consists in bending a rod or wire into the form of a loop but leaving an extension on said loop to form a handle and then producing lips in the inner surface of said loop by swaging the metal thereof inwardly of the loop for the purpose of forming crown lifting projections. 90

2. The method of making an article of the class described, which consists in bending a rod or wire to form a blank embodying a plurality of loops, and then producing a lip in the inner surface of one of said loops by 95 swaging the metal thereof inwardly of the loop for the purpose of forming a crown lifting projection positioned substantially centrally of the wire or rod forming said loop. 100

3. The method of making an article of the class described, which consists in cutting from a source of supply a rod or wire of the length necessary to form the article, bending said rod into a blank embodying two loops, 105 leaving the free ends of the rod unattached, and then producing lips in the inner contour of one of the loops by swaging the metal thereof inwardly from either side of the loop for the purpose of forming crown lifting projections with parallel faces and recesses in the loop adjacent the lips. 110

4. The method of making an article of the class described, which consists in bending a rod or wire to form a blank embodying a plurality of loops, leaving the free ends of the wire or rod unattached, and then producing lips in the inner surface of one of said loops by swaging the metal thereof inwardly of the loop for the purpose of forming substantially flat, crown lifting projections. 115 120

In testimony whereof I have signed my name to this specification.

EDWIN WALKER.
